FIG.1.

FIG.2.

FIG.3.

FIG.4.

FIG.5.

FIG.6.

FIG.7.

FIG. 1 is a perspective view of an air treating unit or similar article, showing the new design;

FIG. 2 is a top plan view thereof;

FIG. 3 is a front elevational view thereof;

FIG. 4 is a side elevational view thereof;

FIG. 5 is a perspective view of a modification of the design for the air treating unit or similar article shown in FIGS. 1 to 4, inclusive; and

FIGS. 6, 7 and 8 are top plan and front and side elevational views, respectively, of the air treating unit or similar article shown in FIG. 5.

The undisclosed side of the air treating unit or similar article is a mirror image of the side shown, and the rear thereof is substantially plain.

The broken line cross-hatching on the sides of the base in FIGS. 1, 4, 5 and 8 represents a patterned area.

The dominant features of the design reside in the portions shown in full lines.

We claim:

The ornamental design for an air treating unit or similar article, substantially as shown and described.
